UNITED STATES PATENT OFFICE.

FRANK W. EMRICK, OF BUCHANAN, IOWA.

CHAIN.

Application filed May 9, 1927. Serial No. 190,065.

This invention relates to chains and its general object is to provide a chain whose construction is an improvement on the disclosure in my patent for chain, No. 1,632,172, dated April 5th, 1927.

Another object of the present invention is to provide a chain composed of links that includes all of the advantageous features of the construction of my previous application, 10 and while the present link also includes sections in their make-up, these sections are formed and joined together in a manner to provide a link that is possessed of maximum strength, and capable of enduring great 15 strain without breaking or disarranging the parts thereof.

This invention also consists in certain other features of construction and in the combination and arrangement of the several 20 parts, to be hereinafter fully described, illustrated in the accompanying drawings and specifically pointed out in the appended claims.

In describing my invention in detail, reference will be had to the accompanying 25 drawings wherein like characters denote like or corresponding parts throughout the several views, and in which:

Figure 1 is a side elevation of a length of 30 chain constructed of links forming the subject matter of the present invention.

Figure 2 is a perspective view of one of the links per se.

Figure 3 is a similar view showing one of 35 the sections of the links before it is bent into link formation.

Figure 4 is a similar view of the respective sections of the present link separated.

Referring to the drawings in detail, the 40 reference numeral 1 broadly indicates a chain which is formed from links constructed in accordance with the present invention and these links are also formed to prevent twisting or kinking of the chain as will be apparent.

The links of the present invention as previously stated are also formed from sections, and these sections are provided from blanks which include arms 2 arranged in cruciform 45 formation as clearly shown in Figure 3. The arms are interconnected midway their ends, curved from their juncture as at 3 and

terminate in straight portions 4 which have their ends 5 arranged in alignment as best shown in Figure 4 of the drawings. 55

The ends of the arms of each section are adapted to be welded, brazed or soldered together, with the result, it will be apparent that the sections are connected midway their ends to provide the complete link as shown 60 in Figure 2.

From the above description and disclosure of the drawings, it will be obvious that I have provided a link which when connected together in numbers as shown in Figure 1, 65 will provide a chain that cannot become twisted due to the peculiar construction of the links and by connecting the sections midway their ends, it will be apparent that the link is possessed of great strength. 70

It is thought from the foregoing description that the advantages and novel features of my invention will be readily apparent.

I desire it to be understood that I may make changes in the construction and in the 75 combination and arrangement of the several parts, provided that such changes fall within the scope of the appended claims.

What I claim is:

1. A chain of the character described 80 comprising links including sections, arms interconnected midway their ends and curved from their juncture, straight portions included in said arms and terminating in alignment with each other, and said straight portions being secured to the straight portions of the companion section of said link. 85

2. A chain of the character described comprising links each including a pair of sections having confronting ends secured together, and said sections being formed from arms of cruciform formation. 90

3. A chain of the character described comprising a plurality of similar connected links, each link being formed of a pair of 95 sections including arms connected midway their ends and curved from their point of connection, straight portions included in said arms and the straight portions of each section being secured together in a manner 100 whereby the point of union is disposed midway the ends of the link.

In testimony whereof I affix my signature.
FRANK W. EMRICK.
